UNITED STATES PATENT OFFICE.

JOHN D. WOODS, OF STEUBENVILLE, OHIO.

INK-WELL.

No. 879,712.

Specification of Letters Patent.

Patented Feb. 18, 1908.

Application filed July 5, 1907. Serial No. 382,329.

To all whom it may concern:

Be it known that I, JOHN D. Woods, a citizen of the United States of America, residing at Steubenville, in the county of Jefferson and State of Ohio, have invented certain new and useful Improvements in Ink-Well, of which the following is a specification, reference being had therein to the accompanying drawing.

10 This invention relates to ink-wells, and more particularly to that class of ink-wells which are non-spillable.

The primary object of the invention is to provide an ink receptacle with a stopper of novel form, and means for automatically seating said stopper in the mouth of the receptacle when the latter is upset.

A further object of the invention is to provide an ink-well comprising a body portion 20 of glass or other vitreous material, and a protecting casing detachably secured to the body portion.

The construction of the improvement will be fully described hereinafter, in connection 25 with the accompanying drawing, which forms a part of this specification, and its features of novelty will be set forth in the appended claims.

In the drawing, Figure 1 is a vertical section of the improved ink-well, with parts shown in elevation. Fig. 2 is a horizontal section of the same, and Fig. 3 is a central vertical section of the device in its upset position showing the mouth thereof closed.

35 The reference numeral 1 designates the body portion of the receptacle which is preferably made of glass, and may be of any preferred general shape, as round or square, the form shown in the drawing being round.

40 This body portion 1 is formed at one side with a vertically disposed semi-circular hollow projection 2 extending throughout the height of said body portion, and communicating at its lower end with a groove 3, formed on the under side of the bottom of the well as shown, and extending across the bottom.

The body portion 1 is screw threaded at its upper end to receive a removable cover 4, having a depending annular internally threaded flange 5 to engage the threads of the well. The cover is also provided with a neck 6 formed with a flaring mouth 7 to receive and closely fit a spherical stopper 8.

55 To one side of the cover 4 is secured a

bracket 9 connected to the mouth 7 by a brace 9^a and provided at its upper end with curved arms 10, which serve to support the stopper as shown in Fig. 1. A ring 11 projects from the stopper 8 and to it is secured one end of a cord 12, said cord extending down within the hollow projection 2, and then under the bottom of the well within the groove 3 and having its lower end secured to an eye 13 projecting from one end of a block 14. To an eye 14^a projecting from the other end of the block a second cord 15 is secured, the free end of which extends through the open end of the groove 3 and is formed into a knot 16. The casing 17, which is preferably of wood, conforms to the exterior contour of the ink receptacle and the latter fits snugly within it.

To secure the casing 17 to the ink-well detachably, I provide a metallic band 18, surrounding the upper end of the casing and secured thereto by screws 19. The upper edge of this band is provided with an inwardly projecting annular flange 20, which overlaps the upper edge of the casing and 80 engages a shoulder 21 formed around the edge of the cover 4, and around the upper edge of the projection 2 as shown in Fig. 1. The flange 5 of the cover extends down within the upper portion of the hollow projection 2 as shown.

Projecting through an opening in the bottom of the casing is a head 23, against which bears the free end of a flat spring 24, the opposite end of which is secured to the 90 under side of the bottom 25 of the casing. The ends and sides of the casing project below the bottom thereof to provide a space for the spring 24.

The numeral 26 designates an internally 95 threaded boss projecting from the upper side of the bottom of the ink-well at one side of its vertical center and within the socket formed by said boss is secured the lower threaded ends of a rod or spindle 27, said rod 100 extending through a countersunk opening in the cover 4, and having a screw head 28. Upon the rod or spindle 27 is slidably supported a spool 29 provided at one side with a perforated lug 30. Above the spool a coil 105 spring 31 surrounds the spindle 27, the lower end of said spring resting upon the upper end of the spool and its upper end bearing against a nut 32 on the spindle below the cover 4.

A chain 33 is secured at one end to the lug 110

30 and the opposite end of said chain extends through a central opening in the stopper 8 and is secured therein by the ring 11 which projects from the stopper.

5 The utility and operation of the improvement will be readily understood. When the ink-well is in its normal position, as shown in Fig. 1, its weight retains the pin 22 in elevated position against the tension of the 10 spring 24, said pin engaging the inner end of the block 14. The placing of the spherical stopper 8 upon the curved arms 10 draws up the spool 29 by the chain connection 33, thus compressing the coil spring 31. In case the 15 ink-well is accidentally upset, the spring 24 forces the pin 22 outward as illustrated in Fig. 3, and this movement of the spring disengages the pin 22 from the block 14, causing the stopper 8 to be quickly seated within the 20 flaring mouth of the ink-well by the expansion of the coil spring 31. It will be apparent that when the receptacle is restored to its upright position the pin 14 will be again forced upward to permit the stopper to 25 be returned to its position upon the arms 10, by pulling upon the cord 15 to reengage the pin and block. The casing 17 is detachably secured to the ink receptacle by thumb screws 34 which pass through openings in the 30 ring 18 and into threaded openings in the casing. The spherical stopper 8 may be removed from its supporting arms 10 by hand to close the mouth 7, a tab 35 being provided for that purpose.

35 I would have it understood that the invention is not restricted to the details of construction here shown and described, but includes all such changes and modifications properly falling within the terms and scope of 40 the claims.

Having fully described my invention, what I claim and desire to secure by Letters Patent is:

1. A non-spillable ink-well comprising a 45 body portion provided with a vertical passage at one side thereof and a bottom groove communicating with said passage, a spring controlled pin below the bottom of the ink-well, a cover provided with a flaring mouth, 50 a stopper fitting said mouth, and means within the receptacle connected to said stopper for seating the latter when said pin is moved by its spring.

2. A non-spillable ink-well comprising a 55 body portion provided with a vertical passage at one side thereof and a bottom groove communicating with said passage, a spring-controlled pin below the bottom of the ink-well, a cover provided with a flaring mouth, 60 a stopper fitting said mouth, and means within the receptacle connected to said stopper for seating the latter when said pin is moved by its spring, said means consisting of a stationary spindle, a spring pressed slide

thereon, and a flexible connection between 65 said slide and stopper.

3. The combination with an ink-well formed at one side with a vertical hollow projection, and at its bottom with a horizontal groove, of a casing within which the ink-well 70 fits, a pin extending centrally through the bottom of the casing, a spring secured at one end to the bottom of the casing, and connected at its opposite end to said pin, a cover detachably connected to said ink-well and 75 provided with a flaring mouth bracket projecting from said cover, and having curved arms, a spherical stopper adapted to rest on said arms, a spring-controlled slide within the ink-well having a flexible connection with 80 said stopper for seating the latter when said pin is forced outward by its spring, a cord attached to said flexible connection and a block carried by said cord to engage said pin.

4. The combination with an ink-well 85 formed with a vertical cord passage at one side and a bottom groove communicating therewith, of a casing within which the ink-well fits, a spring-pressed pin extending centrally through the bottom of the casing, a 90 removable cover provided with a flaring mouth, a bracket projecting from said cover, arms extending from said bracket, a cord extending through said passage and groove, a block secured to said cord, a spherical stopper supported by said arms, a vertically disposed rod or spindle within the ink-well, a 95 spring-pressed slide on said rod or spindle, and a chain connection between said slide and said stopper.

100 5. The combination with a receptacle constituting an ink well, of a removable cover therefor, said cover having a depending flange engaging the said receptacle, said flange having its periphery flush with the 105 periphery of the receptacle, a casing within which said receptacle fits, a band surrounding the casing and provided with an annular inwardly extending flange engaging the cover for maintaining it in position, and means for 110 securing the band to the casing thereby connecting the casing cover and receptacle together.

6. The combination with an ink-well, of a 115 removable cover therefor, provided with a flaring mouth, a spherical stopper fitting said mouth, a chain secured at one end to said stopper and extending through said mouth and spring-controlled means within the ink-well to which the opposite end of said chain 120 is attached for seating said stopper.

In testimony whereof I affix my signature in the presence of two witnesses.

JOHN D. WOODS.
